US0D1045679S

(12) **United States Design Patent** (10) Patent No.: **US D1,045,679 S**
 (45) Date of Patent: ** Oct. 8, 2024

(54) **MOTORCYCLE FRAME SLIDER**

(71) Applicant: **XIN MEI DA TRADING CORPORATION LIMITED**, Hong Kong (CN)

(72) Inventor: **Wai man Yeung**, Hong Kong (CN)

(73) Assignee: **XIN MEI DA TRADING CORPORATION LIMITED**, Hong Kong (CN)

(**) Term: **15 Years**

(21) Appl. No.: **29/926,056**

(22) Filed: **Jan. 29, 2024**

(51) LOC (14) Cl. **12-11**

(52) U.S. Cl.

USPC **D12/114**

(58) **Field of Classification Search**

(57) **CLAIM**

The ornamental design for a motorcycle frame slider, as shown and described.

DESCRIPTION

FIG. 1 is a front perspective view of a motorcycle frame slider, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the motorcycle frame slider, which form no part of the claimed design.

1 Claim, 8 Drawing Sheets
